APPARATUS FOR ABRASIVELY TREATING
METAL OBJECTS

Charles Hayward Hammell, Mishawaka, Ind., assignor to The American Foundry Equipment Company, Mishawaka, Ind., a corporation of Delaware

Application January 29, 1937, Serial No. 122,908

8 Claims.

(Cl. 51—9)

This invention relates to apparatus for abrasively treating metal objects.

In treating metal objects, such as castings and forgings, with a stream of abrasive particles, for the purpose of cleaning, polishing, hardening or otherwise modifying the surface characteristics, it is generally desirable to expose all or predetermined portions of the surfaces of the articles sufficiently to the action of the stream of abrasive or other treating material to effect complete and uniform treatment. Where the articles are small, rugged and suitably shaped they can be conveniently exposed for treatment in a tumbling mill or like apparatus. However, tumbling or the equivalent handling is not suitable in many instances, as for example, where the articles are large and heavy, delicate and brittle, irregularly or awkwardly shaped and have substantial projections, or where they have cavities of substantial depth. In addition, it is often desirable to expose the articles in a predetermined manner in order to insure a complete or a predetermined degree of treatment, which generally cannot be insured by tumbling.

Where relatively large quantities of articles are to be treated, it is desirable to pass them in succession through the abrasive stream in a more or less continuous series to avoid loss of time, power and labor, and to obtain the maximum utilization of the apparatus. Generally, maximum efficiency can best be obtained by providing partial or full automatic operation.

According to the present invention, the article to be treated is suspended by means of a suitable conveyor mechanism which interposes the minimum obstruction to the impingement of the abrasive or other treating material against the article. The article is transported along a predetermined path and into the abrasive stream whereupon the forward movement of the article is retarded or completely halted and the article is turned about in the abrasive stream to expose all or predetermined portions of the surfaces to the abrasive effect of the stream. Each treating stream is projected in a generally fan-like formation whereby the several portions of the stream strike the article at varying angles thereby effectively treating the surfaces of cavities and projections. Preferably, several abrasive streams are established at spaced selected points along the path of movement of the article to insure complete treatment of all portions of the article and at the same time avoid interference between the several streams, or with the apparatus.

The present invention also provides suitable apparatus comprising the combination of one or more centrifugal throwing wheels having means for controlling the direction of flight of the thrown abrasive with a conveyor mechanism for carrying the articles to be treated through a stream or streams. The conveyor mechanism comprises a suitable track having a plurality of suspension devices traveling thereon, each adapted to carry one or more articles to be treated in suspended position. The conveyor is suitably driven to advance the suspension devices along a predetermined path and through the stream or streams of abrasive, a suitable drive mechanism being provided to retard or completely halt the forward movement of the suspension devices for a predetermined period when it is brought into the abrasive stream. Each suspension device is adapted to retard the article while in the stream or streams of abrasive, thereby permitting all portions of the article to be presented to the abrasive stream. Preferably, a suitable housing is provided to enclose the abrasive streams which is provided with suitable entrance and exit openings. The driving mechanisms and like operating parts are disposed outside of the housing and are thus protected from wear and damage which might result from contact with the abrasive material.

30 The present invention provides apparatus by which castings, forgings or other articles can be quickly and effectively cleaned, polished, hardened, or otherwise treated. The invention permits close control of the extent of treatment and insures that all the articles may be treated in a predetermined and uniform manner. The apparatus is rugged and durable and is suitable for continuous and semi-automatic or fully automatic operation.

40 Various other features and advantages of the invention will be apparent from the following particular description and from an inspection of the accompanying drawings.

45 Although the novel features which are believed to be characteristic of this invention will be particularly pointed out in the claims appended hereto, the invention itself as to its objects and advantages, and the manner in which it may be carried out, may be better understood by referring to the following description taken in connection with the accompanying drawings forming a part thereof, in which:

50 55 Fig. 1 is an end elevational view showing one form of apparatus suitable for carrying out the present invention;

Fig. 2 is a top plan view of the apparatus shown in Fig. 1, certain portions of the apparatus being shown in cross section for convenience of illustration;

Fig. 3 is a side elevational view of a portion of the apparatus shown in Fig. 1;

Fig. 4 is a vertical transverse sectional view of the apparatus taken along line 4—4 of Fig. 3;

Fig. 5 is an enlarged fragmentary view partially in cross section showing a portion of one of the suspension devices;

Fig. 6 is an enlarged fragmentary side elevational view of a portion of the structure shown in Fig. 5; and

Fig. 7 is a schematic and partially diagrammatic view of a portion of the conveyor and the wiring diagram of the control system for the conveyor drive.

In the following description and in the claims, various details will be identified by specific names for convenience, but they are intended to be as generic in their application as the art will permit. Like reference characters denote like parts in the several figures of the drawings.

In the drawings accompanying and forming part of this specification, certain specific disclosure of the invention is made for purposes of explanation, but it will be understood that the details may be modified in various respects without departure from the broad aspect of the invention.

The present invention is particularly useful in the treating of articles which are relatively large and heavy and which cannot conveniently be tumbled and which have numerous cavities or projections. One example of such article is a cylinder block casting for automotive engines. For the purposes of illustration, such a casting (designated by the reference character E in the drawings) is shown in connection with the embodiment of the apparatus disclosed herein. However, it is to be understood that the apparatus, according to the present invention, is capable of use with numerous types of castings, forgings and other articles adapted to be suspended while undergoing cleaning treatment.

Referring now particularly to Figs. 1 to 4, the apparatus preferably includes a housing 10 defining a cleaning chamber 11. The housing has an inlet 12 closed by a pair of inwardly swinging doors 13 suitably mounted on hinges 14 and an outlet 15 closed by swinging doors 16, mounted on hinges 17. The doors 13 and 16 are so mounted that they tend to swing to closed position and normally assume this position.

One or more abrasive projectors are associated with the housing for projecting streams of treating material for suitably treating the articles when in predetermined position in the chamber 11. The present apparatus includes three such projectors, denoted by reference characters A, B and C. All of the projectors A, B and C may be similar, and for the purpose of illustration, only one is illustrated and described in detail herein.

Referring now particularly to Fig. 4, the projector comprises a rotary centrifugal wheel 20 having a plurality of spaced throwing blades 21 extending in a generally radial direction from the periphery of the wheel and terminating inwardly short of the center to define a central space 22. Positioned within the space 22 and fixed relatively to the blades 21 to rotate therewith is an impeller 23 having a plurality of radially arranged vanes 24. A tubular control

member 25 surrounds the impeller and is provided with an outlet opening 26. The control member 25 is mounted so as to be stationary relative to the impeller 23 and throwing blades 21 but it may be adjusted for the purpose of controlling the direction of flight of the abrasive.

The throwing blades 21 may be carried by spaced side plates 27, 27' secured together and carried by hub 28 which is mounted on a shaft 29 rotatable in bearings 30 suitably mounted on a mounting plate 19 and additionally supported by a bracket 19'. The wheel 20 may be rotated by motor 31 connected by a suitable drive 32 to the shaft 29.

For convenience, the motor 31 and bearings 30 may be mounted on the mounting plate 19 which may be suitably secured on the upright wall of the housing 10 thereby permitting the motor and wheel to be removed from the housing as a unit. The wheel 20 is mounted adjacent and may project partially through an opening 38 in the plate 19 and the housing side wall. A suitable housing 33 may partially surround the wheel and may be removably attached to the plate 19.

The wheel 20 may be supplied with abrasive through a feed pipe 35 leading from the hopper 36 and extending through an opening 37 in the side plate 27. Upon energization of the motor 31, the impeller 23 and throwing blades 21, together with the side plates 27, 27' rotate as a unit, the control member 25 remaining stationary. Abrasive fed to the impeller 23 is thrown by the impeller vanes through the outlet opening 26 and into the path of the blades 21. The abrasive is urged along the leading faces of the blades 21 and is projected from the blades adjacent the periphery of the wheel by combined centrifugal and rotary forces.

The wheel is rotated at sufficient speed to project the abrasive from the wheel 20 at an abrading velocity and in a fan-like stream and in a controlled direction. The direction of flight and impingement pattern is determined by the shape and adjustment of the control member 25. The stream produces an elongated and generally rectangular impingement pattern, and may extend over a wide angle depending upon the shape and size of the control cage opening and the distance of the wheel from the work. The direction of the stream may be controlled by suitable adjustment of the clock-dial position of the outlet opening 26 in the control cage.

Although the term "abrasive" is used herein to designate the treating material, the term is intended to include all suitable material, such for example, as cracked steel grit, smooth steel shot, quartz sand or other materials suitable for cleaning, polishing, smoothing, hardening or otherwise modifying the surface characteristics of the article to be treated.

Referring to Figs. 2 and 4, the several wheels A, B and C may be spaced longitudinally along the cleaning chamber 11. The wheels may also be disposed at different elevations whereby the streams a, b and c projected by the wheels A, B and C respectively impinge against the article E at different angles. As will be seen from an inspection of Fig. 4, a suitable arrangement of wheels may be made so that all portions of the various surfaces will be treated during the course of the passage of the article E through all of the streams.

Referring now to Figs. 1, 3 and 4, the bottom wall 40 of the housing may be inclined to form a

hopper for collecting spent abrasive and a screen 42 may extend across the bottom of the treating chamber 11 for screening out scale and other particles of foreign matter. The hopper wall 40 may extend to a pit 41 and may lead to the bottom of an elevator 43. The elevator 43 includes an endless belt 44 trained over pulleys 46 and 47 and carrying a plurality of lifting buckets 45. The elevator is driven by motor 48 connected by drive 49 to the pulley 47 and thus spent abrasive may be elevated to an abrasive cleaning chamber 50 from whence it falls by gravity into an abrasive storage chamber 51. The storage chamber 51 may be connected by suitable conduits 52, 53 and 54 to the projectors A, B and C. One or more vents 55 may be provided in the housing top wall for drawing off dust and other finely divided material.

An article-conveyor, preferably of the overhead suspension type, is associated with the housing 10 for advancing articles to be treated therethrough. The conveyor may include upright members 60, longitudinal horizontal members 61 and transverse horizontal members 62 suitably arranged and connected to form a rigid frame for supporting a track 65. The track 65 preferably is arranged in an endless circuit and has a straight line portion extending longitudinally above the housing 10.

A plurality of suspension devices 70 are associated with the track 65, a suitable number being provided for convenient handling of a number of articles or work pieces to be treated. Referring now to Figs. 4 and 5, each suspension device 70 includes a hook 71 carried on or integral with a vertical shaft 72 and having a generally horizontal or upturned article-engaging portion 73 which preferably terminates in an upturned end 74. The shaft 72 extends into an opening 77 in a bearing member 75 and is retained therein by a collar 76 secured to the shaft 72 cooperating with a shoulder 78. A thrust bearing 79 may be interposed between the shoulder 78 and the collar 76 to minimize friction. The opening 77 may be closed by a plate 80 suitably secured as by one or more screws 81.

The suspension device 70 may be suspended from the track 65 by a hanger plate 82 secured to the bearing member 75 and having a pair of rollers 83 rotatably mounted on pins 84 fixed to the plate. A second hanger plate 85 having its upper end spaced from and generally parallel to the hanger plate 82 and carries a pair of rollers 83 similar to the first set of rollers. The hanger plate 85 has a generally Z-shaped cross section and is formed with a horizontal portion 86 and a depending portion 87, the latter of which is secured as by rivets 88 to the corresponding portion of the hanger plate 82.

A drive chain 90, which may be of the link type, may extend along the series of suspension devices 70 and may be connected to each of the devices by a bracket 92 suitably attached to one of the links 91 and to the horizontal portion or shoulder 86 of the suspension plate 85 as by welding or riveting. The chain 90 may be guided and may be supported intermediate the suspension devices 70 by a guide track 93 and carried by one or more hangers 94 depending from the horizontal members 62 of the frame.

The drive chain 90 is trained around a plurality of sprockets 100 suitably mounted for rotation on the conveyor frame. Each sprocket 100 is mounted on a shaft 101 journaled in a lower bearing 102 carried on a cross member 103 and in an upper

bearing 104 carried on a cross member 105. The shaft 101 may be retained in its bearings by collars 106 and 107 or other suitable means. The sprockets 100 are positioned preferably at the corners of the generally rectangular figure defined by the track 65 and the radius of each sprocket 100 preferably corresponds with the radius of the corresponding portion of the track 65; thus each sprocket 100 is in engagement with the chain over a substantial portion of the circumference of the sprocket.

One or more of the sprockets 100 may be suitably driven to cause the chain 90 to move the suspension devices 70 along the track 65. A motor 110 may be mounted on a plate 111 supported on the horizontal members 62 and may be connected through a suitable driving mechanism 112, preferably of the speed reducing type, to the shaft 101 of the drive sprocket 100. Upon energization of the motor 110, the connected drive sprocket 100 is rotated and thus causes the chain to draw the suspension devices 70 along the track 65 and through the treating chamber 11.

Referring to Fig. 4, provision is made for admitting the hook and shaft portion of each suspension device 70 to the housing 10. As previously described, the doors 13 and 16 are pivotally mounted and can be forced open by applying pressure thereto in the proper direction. Extending upwardly from the inlet opening 12 is a slot 96 positioned to permit the shaft 72 of the suspension device 70 to pass through the end wall of the housing 10. An elongated slot 93 is formed in the top wall of the housing 10 longitudinally of the housing and in position to permit the shaft 72 to pass therethrough and thereby permit the suspension device 70 to be moved relatively along the housing 10 with its lower end in the treating chamber 11. The opening 93 may be normally closed by a pair of flexible sealing members 94 clamped to the top wall of the housing clamping plates or members 95. The sealing members 94 permit the shaft 72 to pass along the slot 93, but owing to their resiliency, spring back into engagement closing the opening immediately upon the passing of the shaft 72. If desired, sealing arrangements similar to those provided for the top slot 93 may be provided for the end slots 96.

Suitable means may be provided for rotating the suspension devices 70 throughout at least a portion of their travel and particularly during the time they are under treatment by the abrasive projecting devices A, B and C.

Referring now particularly to Figs. 5 and 6, each suspension element 70 may be provided with a gear 140 mounted on the shaft 72 and fixed against rotation by a suitable means, such as a key 141. The gear 140 may be supported on the shaft as by a pin 142.

Referring now particularly to Figs. 2 and 4, there is provided an endless driving element, such as a chain 143, trained over driving gears 144 and 145. The driving gears 144 and 145 are mounted on shafts 146, 147 respectively, which in turn are rotatably mounted in bearings 148 and 149. The chain 143 may be provided with guides 150 and 151 which may be supported on the top wall of the housing by brackets 152.

The drive chain 143 may be driven from a motor 155 which is connected through a suitable speed reducer 156 and drive 157 to the shaft 147.

It will be seen that when the chain 143 is driven in a direction indicated by the arrows in Fig. 2, it causes clockwise rotation (as viewed in Fig. 2) of all of the gears 140 which are in po-

sition to be engaged by the chain 143. This rotation is imparted to the corresponding hooks 71 and the articles E carried thereby.

The driving arrangement for the suspension devices is designed to retard or completely halt each suspension device successively opposite the several abrasive projectors A, B, C whereby the article carried by the suspension device is retained in each abrasive stream a, b, c for a sufficient period to treat the article to the desired extent. In the present embodiment of the invention, the driving arrangement is arranged to completely halt the suspension device for a predetermined period adjacent each of the projectors. This halting is preferably accomplished by cutting off the supply of electric energy flowing to the motor 110.

Referring now to Fig. 7, there is shown more or less diagrammatically one form of mechanism for intermittently halting the driving motor 110. Supply conductors 115 and 116 are provided for connecting on an electric motor 110 to a suitable source of power. A main switch 117 is connected in circuit with the motor as by conductors 118, 119 leading to a movable contact 120 and conductors 121, 122 leading from a stationary contact 123 to the motor 110. A return conductor 124 leads from the motor 110 to the supply conductor 116.

The switch 117 preferably includes a spring 125 or equivalent means for normally biasing the movable contact 120 into engagement with one or the other of the stationary contacts 123 and 127. An actuating arm 126 may be mechanically connected to movable contact 120 and lies in the path of the suspension member 70 for actuation thereby. Preferably, the actuating arm 126 is positioned to be engaged by the plate 82 of each suspension member 70 and to be rotated to move the contact 120 away from the contact 123 and into engagement with a stationary contact 127.

The timing mechanism 128 may be provided for closing the motor circuit a predetermined interval after the main switch 117 has been opened, thereby causing the motor to move the suspension device 70 away from the switch 117 and thus permitting the switch 117 to again close on the contact 123.

The timing mechanism 128 may be of any suitable construction and may include a switch 131 connected in the motor circuit by conductors 133 and 134. A slow acting relay 135 or other timing means may be mechanically connected to the movable contact 132 and may be connected between the stationary contact 127 and supply conductor 115 by conductors 129, 130 and 118 whereby it is energized to close the switch with a delayed action, when the main switch 117 is closed on the contact 127.

A pivoted reset lever 136 is connected as by a link 137 to the arm 126 for returning the contact 120 to its initial position when the suspension device 70 passes. The operation of the timing mechanism is as follows:

Assuming no suspension device 70 to be in engagement with the actuating arm 126, the switch 117 is closed on the contact 123 and the motor 110 is thereby connected to the supply conductors 115 and 116 and is energized to move the suspension devices 70 along their path of movement.

When the first suspension device 70 moves into engagement with the actuating arm 126, it causes the contact 120 to be moved away from the contact 123 thereby interrupting the motor circuit

and halting the motor. The contact 120, however, is snapped by the spring 125 and immediately closes on the contact 127 and completes a circuit through the relay 135 or other timing mechanism, which operates, after a predetermined interval, to close the switch 131. The closing of the switch 131 completes a circuit through the motor and re-energizes the motor which thereby moves the suspension member 70 away from the actuating arm 126. As the suspension device 70 moves past the reset lever 136, the switch is thereby closed on the contact 123 and the circuit through contact 127 and the solenoid 135 is broken.

The motor 110 continues to drive the suspension devices 70 until the next suspension device moves into engagement with the actuating arm 126 and the previously described cycle is again initiated. The relay 135 is made to act with sufficient delay so that each suspension device 70 is halted for a sufficient time in position adjacent each projector to permit the work piece E to be exposed to the stream for a sufficient period to accomplish the desired treatment.

The general operation of the apparatus is as follows:

The supply conductors 115 and 116 are connected to a source of power and the motor 110 is thus energized to actuate the drive chain 90 and move the suspension devices 70 intermittently around the path defined by the track 65. The motor 155 is also energized to drive the chain 143, as above described.

The articles to be treated are placed on the hooks 71 at any convenient point along the path of movement of the suspension devices 70 and thereafter are carried by the suspension devices into the treating chamber 11. As the suspension device approaches the inlet doors 13, the doors are forced open by the pressure of each suspension device 70 and its load to admit the article E and thereafter swing closed to completely seal the suspension chamber. The shaft 72 passes through the slot 96 and rides along the slot 93 without any substantial interference.

The control apparatus is operated as above described and periodically halts the driving mechanism, thus causing the suspension devices 70 to halt in position for a predetermined period. The apparatus and control mechanism are so designed that each suspension device preferably halts while opposite each of the projectors A, B, C, thus exposing the article E to the effect of each of the abrasive streams.

The driving chain 143 is adapted to engage each gear 140 prior to or at the time the first suspension device reaches its position opposite the first abrasive projector A, thus causing the suspension device to be continuously rotated during the time it is opposite the abrasive projector A. This rotation of the article E, combined with the divergent direction of several paths of the abrasive particles thrown by the projector A, causes the article E to be fully and completely exposed to the abrasive treatment.

The control mechanism then operates to actuate the driving mechanism and advance the suspension member 70 to a position opposite the second abrasive projector B, wherein the suspension member is halted and the article exposed to treatment by the stream b. Thereafter, the suspension device is then moved to position opposite the projector C where it is again treated. The drive is again energized and moves the suspension device 70 and finally, the articles are

carried out of the housing 10 whereafter the article E may be removed from the hook 11 at any convenient point.

The present invention provides apparatus whereby all portions of an article may be treated to the desired extent since the article is suspended in a manner which presents the minimum interference with the flight of the abrasive particles and the article is rotated about in the stream to expose the various surfaces to the stream. Furthermore, each stream is projected in a fan-like formation in which the several portions of the stream travel at various angles and the several streams are directed at different angles. Thus, all faces, cavities, projections and other irregular surface portions are struck by the abrasive particles.

The apparatus provides positive manipulation of the articles to be treated and thus uniformity of treatment may be obtained, thereby insuring against over or under treating. The apparatus may be made automatic or semi-automatic and thus requires a minimum of attention on the part of an operator.

The articles are handled in a convenient and efficient manner which permits rapid loading and unloading and which insures against breakage or damage of the work piece since there is no jarring or tumbling. The conveyor track may, if desired, be inserted in a production-line conveyor track and thus the abrasive treating of the castings and forgings may be made an integral part of a complete production line or system.

While certain novel features of the invention have been disclosed and are pointed out in the annexed claims, it will be understood that various omissions, substitutions and changes may be made by those skilled in the art without departing from the spirit of the invention.

What is claimed is:

1. Apparatus for blast cleaning castings, forgings and like articles which apparatus includes, relatively fixed means for establishing a stream of abrasive particles traveling at blasting velocities, conveyor means including hangers adapted to advance articles to be cleaned through said stream in suspended position, driving means for said conveyor, control means actuated by the movement of said hangers past said control means for periodically halting said conveyor when said articles are in said abrasive stream, and means driven independently of said advancing means for rotating each of said articles before, during and after they are in said stream.

2. Apparatus for blast cleaning castings, forgings and like articles which apparatus includes abrasive throwing wheels at a plurality of spaced stations for establishing differently directed streams of abrasive particles traveling at blasting velocities, conveyor means including hangers adapted to advance articles to be cleaned through said streams in suspended position, driving means for said conveyor, an electric motor for driving said conveyor means, electric control means actuated by the movement of said hangers past said control means for periodically halting said conveyor driving motor when said articles are in each of said abrasive streams, and means operated independently of said conveyor advancing motor for rotating each of said articles before, during and after they are in each of said streams.

3. Apparatus for blast cleaning castings, forgings and like articles which apparatus includes, means comprising an abrasive projector of the

5 rotary centrifugal type for projecting a stream of abrasive particles at blasting velocities, conveyor means for advancing articles through said stream, said conveyor means including a stationary track, a plurality of suspension devices mounted for movement along said track, an endless drive chain connected to said suspension devices for advancing said devices along a circuitous path, a driving motor associated with said endless chain, and means for rotating said suspension devices including a driven member mounted on each of said suspension devices, a driving member driven independently of said driving motor disposed adjacent the path of and adapted to engage each of said suspension members during at least the portion of their path wherein they pass through the abrasive stream, control means having an actuating mechanism in the path of and engageable by said suspension devices for controlling the energization of said motor for halting the advance movement of said suspension devices for a predetermined interval when said article under treatment is positioned in the path of the abrasive stream.

20 4. Apparatus for blast cleaning castings, forgings and the like which apparatus includes, a stationary track, a plurality of suspension devices mounted on said track each adapted to suspend one or more articles to be treated, a plurality of 25 abrasive projectors of the rotary centrifugal type each adapted to project a stream of abrasive particles at blasting velocities in a fan-like stream, one of said projectors being adjusted and positioned to project a stream of particles against the 30 top and at least a portion of the side faces of an article carried by said conveyor, and another of said projectors being adjusted and positioned to project a stream of particles against the bottom and at least a portion of the side faces of 35 said article, means for advancing said suspension devices through said streams, means for rotating said article before, during and after it passes through said streams, and automatic timing mechanism operative to halt the advancing 40 movement of each of said suspension devices for a predetermined time interval when the article supported thereon is positioned in the path of each of said streams, said mechanism including a trip member disposed in the path of said suspension devices for actuation thereby.

45 5. Apparatus for blast cleaning metallic articles including, a movable conveyor, a suspension device attached to said conveyor for suspending the article to be cleaned, an abrasive throwing wheel on each side of the path of movement of the said conveyor, each of said wheels having control means associated therewith operative to direct a fan-shaped stream of abrasive against the article moved into the path of said streams and between said wheels, a housing enclosing said streams and the article under treatment, means for rotating said suspension device when the article supported thereby is within the path of each abrasive stream, a time switch, a motor for driving said conveyor, and a trip element connected in circuit with said time switch and said motor, said trip element being positioned to be engaged by said suspension device when the article supported thereon is in said abrasive stream, where 50 by said conveyor advancing motor is halted for a predetermined time interval during rotation of the article in said stream.

60 6. Apparatus for blast cleaning metallic articles including, a track, a carriage movable in a linear direction along said track, a suspension de-

vice rotatably connected to said carriage for rotatably suspending the article to be cleaned, an abrasive throwing wheel on each side of said track and positioned below the same, each of said wheels having control means associated therewith operative to direct a fan-shaped stream of abrasive against the article moved into the path of said streams and between said wheels, means for rotating said suspension device when the article supported thereby is within the path of said abrasive streams, a driving element for linearly advancing said carriage, a motor operating said driving element, a time switch operatively connected to said motor, and means connected in circuit with said time switch and said motor adapted to be engaged by said carriage to halt the operation of said motor and the linear advance movement of said carriage for a predetermined time interval while the article supported on said suspension device is positioned in each of said streams.

7. In apparatus for blast cleaning metal articles including in combination, an I-beam track, a suspended article supporting hanger movable along said track, said hanger including paired rollers running on said track, a U-bracket suspended from said paired rollers having a downwardly extending shank extension, a bearing collar fixed to said shank extension, a thrust bearing supported by said collar, a suspension rod supported by said thrust bearing extending downwardly substantially in vertical alignment with said track, said suspension rod having a hook portion at the lower end thereof from which articles may be suspended, and an endless hanger driving chain having a run thereof extending under said track, means for securing said hanger driving chain to said bracket, a fixed guide member for supporting said run of the hanger driving chain in position generally parallel to said track, means for driving said hanger chain, a sprocket fixed to said suspension rod below said bearing collar, a continuous sprocket driving chain having one run thereof extending along said track

in position for engagement with said sprocket, means for independently driving said sprocket chain to rotate said suspension rod and the article suspended therefrom, and a U-shaped guide member extending along the sprocket engaging run of said sprocket chain preventing lateral displacement thereof in one direction and exposing said sprocket chain to engagement from the opposite direction of said sprocket.

8. In apparatus for blast cleaning metal articles including in combination, a circuitous overhead track, a suspended article supporting hanger movable along said track, said hanger including paired rollers running on said track, a U-bracket suspended from said paired rollers having a downwardly extending shank extension, a bearing collar fixed to said shank extension, a thrust bearing supported by said collar, a suspension rod supported by said thrust bearing extending downwardly substantially in vertical alignment with said track, said suspension rod having a hook portion at the lower end thereof from which the articles may be suspended, and an endless hanger driving chain having a run thereof extending under said track, means for securing said chain to said bracket, a stationary guide member for supporting said run of the hanger driving chain in a position generally parallel to said track, spaced elements for suspending said guide member from said track, means for driving said hanger chain, a sprocket fixed to said suspension rod below said bearing collar, a continuous sprocket driving chain having one run thereof extending along said track in position for engagement with said sprocket, means for independently driving said sprocket chain to rotate said suspension rod and the articles suspended therefrom, and a guide member extending along the sprocket engaging run of said sprocket chain preventing lateral displacement thereof in one direction and exposing said sprocket chain to engagement from the opposite direction of said sprocket.

CHARLES HAYWARD HAMMELL.
